(57) CLAIM

The ornamental design for athletic pants, as shown and described.

DESCRIPTION

FIG. 1 is a front perspective view of the athletic pants of the present design;

FIG. 2 is a front view of the athletic pants of FIG. 1, showing the design; and,

FIG. 3 is a rear view of the athletic pants of FIG. 1, showing the design.

The evenly spaced dotted lines represent unclaimed stitching. The broken lines at the opening of the athletic pants represent unclaimed subject matter.

1 Claim, 3 Drawing Sheets

FIG. 3
